UNITED STATES PATENT OFFICE.

CHARLES A. BRIMMER, OF SPRING GREEN, WISCONSIN, ASSIGNOR TO ENGELBERT B. SCHWARTZ, OF SPRING GREEN, WISCONSIN.

MILK-SHEET AND RECORD HOLDER.

1,099,015.

Specification of Letters Patent.

Patented June 2, 1914.

Application filed January 30, 1913. Serial No. 745,230.

To all whom it may concern:

Be it known that I, CHARLES A. BRIMMER, a citizen of the United States, residing at Spring Green, in the county of Sauk, State of Wisconsin, have invented certain new and useful Improvements in Milk-Sheet and Record Holders; and I do hereby declare the following to be a full, clear, and exact description of the invention, such as will 10 enable others skilled in the art to which it appertains to make and use the same.

This invention relates to milk sheet holders and has for an object to provide a device of this character having a novel sliding leaf 15 in the cover to conceal or expose the milk sheet as desired.

A further object is to provide means for preventing access of dust into the holder.

With the above objects in view the invention 20 consists of certain novel details of construction and combination of parts herein-after fully described and claimed, it being understood that various modifications may be made in the minor details of construction 25 within the scope of the appended claim.

In the accompanying drawing illustrating this invention:—Figure 1 is a plan view of the invention. Fig. 2 is a plan view with the cover rocked open. Fig. 3 is a cross 30 sectional view on line 3—3 Fig. 1. Fig. 4 is a cross sectional view similar to Fig. 3 but showing the sliding leaf closed. Fig. 5 is a front elevation. Fig. 6 is a fragmentary sectional view on line 6—6 Fig. 5.

Referring now to the drawing in which like characters of reference designate similar parts, 10 designates a casing which is equipped with a hinged cover 11. Mounted longitudinally in the casing are parallel 40 supply and receiving rollers 12 and 13 which are located on opposite sides of a table 14. These rollers carry a tally sheet 15 of which the ends are attached respectively to the rollers by means of clamp strips 16. The 45 spindles of the rollers are extended beyond the ends of the casing and are equipped with buttons 17 for actuating the rollers.

The cover 11 is provided on the inner face of the rear wall and end walls with a 50 groove 18 in which is fitted a longitudinal sight glass 19 equal in width to one-half the width of the top, there being a thin sheet

metal plate 20 also marginally secured in the groove underneath and coinciding with the sight glass. A designation sheet 21 of 55 any desired character is clamped between the sight glass and plate. The plate bears with its free edge upon the tally sheet and firmly holds the latter against the table so that dust and the like is prevented from access to the interior of the casing.

A sliding leaf 22 is fitted at the ends in the groove 18 and is adapted to engage with the rear edge the forward edges of the sight glass and plate and in this position conceals that portion of the tally sheet disposed on the table. When withdrawn forwardly 65 from engagement with the sight glass and plate, the leaf exposes that portion of the tally sheet disposed on the table so that a longitudinal slot exists between the rear edge of the leaf and forward edges of the sight glass and plate through which a pencil 70 may be inserted to apply such memoranda to the tally sheet as it may be desired to 75 preserve.

For limiting sliding movement of the sliding leaf an elongated notch 23 is formed in each end edge of the leaf and receives a pin 80 24 that projects from the adjacent inner wall of the groove. These pins contact with the end walls of the notches and limit sliding movement of the leaf in either direction. A grip 25 is fixed to the underneath face of the sliding leaf for manipulating the leaf, 85 the grip being equipped with a depending eye 26 through which a swivel hook 27 carried by the casing may be engaged when the leaf is slid to its inner limit of movement to lock the leaf in this position.

It will thus be seen that I have provided 90 an extremely simple and inexpensive tally sheet holder that is practically dust-proof and may be easily manipulated to expose or conceal that portion of the tally sheet disposed on the writing table.

What is claimed, is:—

A tally sheet holder comprising a casing, 100 a writing table extending transversely in said casing, a supply roller and a take up roller on opposite sides of said table and adapted to conduct a tally sheet over said table, a hinged cover for said casing, a member in said cover adapted to support a des-

ignation sheet, a sight glass in said cover above said member adapted to expose and to clamp the designation sheet to said member, a slide leaf in said cover abutting the confronting edges of said member and normally concealing said table, a grip on said leaf for sliding the leaf to expose said table, and a lug on the edge of said leaf fitting in a slot

in said cover and limiting movement of said leaf in each direction.

In testimony whereof, I affix my signature, in the presence of two witnesses.

CHARLES A. BRIMMER.
